UNITED STATES PATENT OFFICE.

WILLIAM H. BENTLEY, OF WESTFORD, NEW YORK.

IMPROVEMENT IN HAY-LOADING MACHINES.

Specification forming part of Letters Patent No. 40,598, dated November 17, 1863.

To all whom it may concern:

Be it known that I, WILLIAM H. BENTLEY, of Westford, in the county of Otsego and State of New York, have invented a new and improved implement or device for elevating hay from the windrow in the field and loading wagons or carts with the same; and I do hereby declare that the following is a full, clear, and exact description of the same, reference being had to the accompanying drawings, making a part of this specification, in which—

Figure 1 is a side sectional view of my invention, taken in the line $x x$, Fig. 2; Fig. 2, a plan or top view of the same; Fig. 3, a transverse section of the same, taken in the line $y y$, Fig. 1.

Similar letters of reference indicate corresponding parts in the several figures.

To enable those skilled in the art to fully understand and construct my invention, I will proceed to describe it.

A represents a frame, which is composed of two parallel side pieces, $a a$, connected at their back ends by a cross-bar, b , and at their front ends by a cross-board, c , which has a rake, B, attached to it. The teeth d of this rake are slightly curved, and rest at their front ends upon the ground. To the side pieces, $a a$, there are attached two inclined bars, $e e$, between which an endless apron, C, is fitted. This apron works over rollers D D, the lower one being fitted between the side pieces, $a a$, and the upper one being fitted between the upper parts of the bars $e e$. Motion is given the apron C through the medium of the lower roller D, which is rotated by means of gears f from the axle E of the wheels F F, which supports the front end of the frame A. The upper side of the apron C is supported by a board, g, which has a groove, h, made longitudinally and centrally in it. The upper end of the board g rests on a cross-bar, i, which is just below the upper roller D, and this roller D has a groove, i', made centrally and circumferentially in it, into which a projection, j, at the center of the upper end of the board g, fits. The endless apron C is formed of a series of parallel wires, k, which are connected at their centers by links l, and the outer ends of the wires k are connected to straps m m, of leather or other suitable material. The apron C has a small rake-head, G, attached to it. This rake-head may be of metal and provided with three prongs, n n n,

which project outward from the apron. The inner part, n' , of the rake-head is bent so as to be at right angles with the outer part, and said inner part works in the groove h of the board g and in the groove i' of the upper roller D. This rake-head works freely on one of the wires k.

H represents an inclined discharging-board, which is connected by hooks or joints o to the upper and back part of the framing of the machine, and said board is supported by a handle, I, the lower end of which is attached by a joint to the cross-bar b of the side pieces, $a a$. (See Fig. 1.) To the center of the cross-bar b there is attached a caster-wheel, J. This caster-wheel is fitted in a spring, K, which is attached to the cross-bar b, said spring admitting of a certain degree of elasticity to enable the implement to conform to the inequalities of the ground over which it may pass. The spring K is attached to the cross-bar b by means of a pivot, g, which allows the caster-wheel to turn readily to suit the direction in which the implement moves. When the implement or device is not at work it may be drawn from place to place by means of the handle I, the upper end of the latter being removed from underneath the discharging-board H.

The operation is as follows: The implement is either attached to one side of a wagon or has a team attached directly to it, so as to be drawn separately by the side of a wagon or cart. The implement is drawn along in line with a windrow, and the rake B takes up the hay and the endless apron C carries the hay up to the discharging-board H, the hay being discharged from the apron in passing over the upper roller D. The rake-head G serves to catch the hay and hold it while being carried up by the apron C, and any suitable number of these heads may be employed as occasion may require. The heads G are retained while at work in a proper outward position from the apron C in consequence of their inner ends, u' , bearing against the board g in the groove h thereof, and said heads G are allowed to fall back toward the apron when passing over the upper roller D, in consequence of their inner ends, u' , passing into the grooves i' of the upper roller, the groove i' being considerably deeper than the groove h in the board g. This falling back of the rake-head

G is necessary to admit of the latter passing the inner edge of the discharging-board H. The discharging-board H conducts the hay into the body of the wagon or cart, which is shown in red outline in Fig. 2.

I would remark that the inclined bars *e e* are supported at their parts by uprights *a'*.

Having thus described my invention, what I claim as new, and desire to secure by Letters Patent, is—

1. The arrangement of the rake-heads G, grooved board *h*, and grooved roller D with

the apron C, rake B, and discharging-board H, all in the manner herein shown and described.

2. The arrangement of the caster-wheel J, spring K, and brace-handle I with the frame A, all in the manner herein shown and described.

WM. H. BENTLEY.
